GARBAGE GRINDER

George R. Coss, Detroit, Mich., assignor to Eureka
Williams Corporation, a corporation of Michigan

Application February 8, 1946, Serial No. 646,397

9 Claims. (Cl. 4—187)

1

This invention relates to garbage grinders.

The invention contemplates a new and improved construction for garbage grinder and has particular reference to a simple and efficient construction by means of which the parts of the apparatus may be efficiently and inexpensively made and assembled to each other and to the drain outlet of a sink.

Principal objects of the invention are to provide:

A new and improved garbage grinder;

A garbage grinder embodying a new and improved arrangement for securing the grinder to the drain outlet of a sink;

A garbage grinder embodying a new and improved construction and arrangement for the parts thereof which makes it possible to efficiently make and assemble the parts to each other and to install the grinder in connection with the drain outlet of a sink.

Other and further objects of the invention will be apparent from the following description and claims and will be understood by reference to the accompanying drawings, of which there are two sheets, which, by way of illustration, show a preferred embodiment and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims. I also contemplate that of the several different features of my invention, certain ones thereof may be advantageously employed in some applications separate and apart from the remainder of the features.

In the drawings:

Fig. 1 is a vertical sectional view of an apparatus embodying the invention;

Fig. 2 is a sectional view taken along the line 2—2 of Fig. 1;

Fig. 3 is a sectional view taken along the staggered line 3—3 of Fig. 1;

Fig. 4 is a plan view of the cover; and

Fig. 5 is a diagrammatic view of the circuit for the grinder motor.

The garbage grinder embodying the invention comprises a casing 10 providing a chamber 12, the inlet 14 of which is connected to the drain outlet 16 of a sink 18. The chamber 12 is adapted to receive garbage and the like material which is to be reduced. The chamber 12 is provided with reducing means for reducing the garbage

2

to a state where the same may be washed down the drain and carried away by water through the drain and sewage system to which the drain is connected. For this purpose, the outlet from the chamber 12 is connected to the drain system for the sink; in fact, the chamber 12 forms a part of the drain system to which the outlet 16 of the sink is connected. For a more complete disclosure of one form of reducing means, reference may be had to the prior copending application of George R. Cross et al., Serial No. 564,118, filed November 18, 1944, for Garbage grinder, now Patent No. 2,421,014.

In the present instance, the drain outlet 16 of the sink is provided by a collar 17 having an upper laterally extending flange 20 which is adapted to rest upon the bottom wall of the sink 18 around the opening therein through which the collar 17 projects. Adjacent its lower end, the outside of the collar is provided with a groove 22. A sleeve 24 is fitted over the grooved end of the collar 17 and is provided with a shoulder 26 which seats against the bottom rim of the collar 17.

The sleeve 24 is provided with a series of circumferentially spaced holes 28 (three or more), each of which has arranged therein a ball 30. The diameter of each ball 30 is greater than the wall thickness of the sleeve 24. The balls 30 are adapted to project into the groove 22 to thereby secure the sleeve 24 to the collar 17. A ring 32 fitted around the sleeve 24 closes the outer ends of the holes 28 in which the balls 30 are arranged and positions the balls 30 in the groove 22. The ring 32, however, is provided with a series of pockets 34 which are adapted to be aligned with the holes 28 by rotational shifting of the ring 32 relative to the sleeve 24 so as to permit the balls 30 to move outwardly of the groove 22 to thereby permit axial separation of the sleeve 24 from the collar 17. The ring 32 is held in position by a series of bolts 36, each of which is threadedly engaged in a threaded hole in the ring 32 and has a head 38 which bears against a channel ring 40 which supports a gasket or sealing ring 42. By adjustment of the bolts 36, the sealing ring 42 which has a close fit on the outside of the collar 17 may be firmly seated against the bottom wall of the sink 18 around the opening through which the collar 17 projects. The ring 32 is thus firmly seated against the sleeve 24.

A sealing ring 44 is carried by the outwardly projecting flange 46 on the sleeve 24. The sealing ring 44 is constructed and arranged to receive the upper inturned rim 48 of the casing 10. Before

the bolts 36 are tightened, the casing 10 may be shifted about its axis so as to properly position the spout 50 defining the outlet from the garbage grinder relative to the drain pipe to which it is to be connected. The ring 32 is sealed between the sealing ring 44 and snap ring 56 which is carried by the upper end of the sleeve 24 on the outside thereof.

The lower end of the casing 10 is provided with an outwardly projecting channel-shaped flange 60 and an internal shoulder 62 which is adapted to seat upon the upper edge 64 of a shredding ring 66. The shredding ring 66 comprises a band which extends around the chamber 12 at the lower end thereof and is provided with a series of cutting teeth or projections 68 disposed around the periphery of the chamber 12 at the bottom thereof and a series of relatively small laterally extending holes 70 which define the outlet from the bottom of the chamber 12. The shredding ring 66 is seated upon an annular shoulder 72 formed on the base member 74 which defines the bottom wall of the chamber 12. The base member 74 is formed to provide a trough 76 into which reduced material and water will be ejected from the chamber 12 through the openings 70 and the ring 66. The trough 76 terminates in the spout 50. The channel-shaped ring 60 of the casing 10 is seated upon an annular shoulder 78 provided by the base member 74. A sealing ring 80, however, is interposed between the flange 60 and the seat 78. An L-shaped ring 82 is arranged to overlie the channel-shaped ring 70 and to project downwardly over the seat 78. A series of bolts 84 threadedly secured in threaded holes in the seat 78 are arranged to clamp the flange 60 and the gasket 80 against the seat 78 so as to provide a fluidtight joint therebetween. The base member 74 is provided with a central opening through which a shaft 86 of the motor 88 projects upwardly into the chamber 12. A seal 90 is arranged to provide a running seal between the bottom wall of the chamber 12 and the shaft 86. The shaft 86 is provided with rotary means such as one or more impellers for impelling material in the bottom of the chamber 12 against the teeth 68 and for projecting reduced material outwardly through the opening 70.

A switch housing 100 is detachably secured by means of bolts 102 to the ring 32 (Fig. 3). A switch 104 is suitably secured in the housing and includes contacts which are normally open. A pin 106 slidably mounted in the wall of the switch 104 is adapted upon being moved to the left to close the switch contacts. The switch is arranged in the circuit of the motor 88 as illustrated in Fig. 5 and normally keeps the circuit open but is adapted to be closed to close the motor circuit so as to energize the motor 88 and the garbage grinder reducing means driven thereby at such times as desired. A pin 108 is slidably mounted in a bushing 110 and has one end thereof projecting through an opening in the sleeve 24 into the throat of the sink drain opening 16 while the other end of the pin is arranged to engage the switch actuating pin 106. A leaf spring 112 pinned at 114 to a wall of the switch housing 100 is arranged between the pins 106 and 108 and biases the pin 108 away from the pin 106 so that the spring pressure on the pin 106 will function to position the pin 106 so that the switch contacts will be open. The construction of the switch 104 may be of any conventional or desired arrangement and hence it is not considered necessary to illustrate the details thereof.

The pin 108 is adapted to be engaged by a part of the cover 120 and shifted thereby so as to close the switch 104. The cover comprises a cylindrical body 122 provided with handles 124 and 126 on opposite sides thereof. The outside of the body 122 is provided with a series of projections or ribs 128 and 129 which are adapted to engage and rest upon an inwardly projecting bead 130 formed on the collar 17 thereby to position the cover 120 in the outlet 16 from the sink. However, the ribs 128 and 129 will space the outer wall of the cover 120 from the inner wall of the collar 17 so as to define a passage therebetween through which water will flow from the sink through the outlet thereof into the chamber 12 of the garbage grinder. In the position in which the cover 120 is arranged as shown in Figs. 1 and 3, a rib 131 on the outer surface of the body 122 is engaging the outer end of the pin 108, thereby closing the switch 104. However, when the cover 120 is shifted so that the rib 131 is not engaging the pin 108, the switch 104 will be open. The cover further includes a plate 140 and an annular sealing ring 142 which is held in position by the plate 140 which in turn is secured to the body 122 by the handle 124. When the cover 120 is removed from the outlet 16 and turned over so that the handle 124 is on the lower side thereof and then re-positioned in the outlet 16, the sealing ring 142 will engage the inner surface of the bead 130 so as to establish a seal between the cover 120 and the inner surface of the collar 17, thereby to prevent the flow of water from the sink to the drain outlet therefrom.

It will thus be observed that the cover 120 may be positioned in the drain outlet 16 in one position so as to close the motor circuit and to permit drainage of water from the sink into the chamber 12; in another position with the switch 104

open while permitting drainage of water through the outlet 16 into the chamber 12; and in a third position with the switch 104 open while the drain outlet 16 is closed to the flow of water from the sink 18.

The construction of the closure actuated switch and related features are disclosed and claimed in my copending application, Serial No. 646,396, filed Feb. 8, 1946, for Garbage grinders apparatus.

While I have illustrated and described a preferred embodiment of my invention, it is understood that this is capable of modification, and I therefore do not wish to be limited to the precise details set forth, but desire to avail myself of such changes and alterations as fall within the purview of the following claims.

I claim:

1. In a garbage grinder adapted to be secured to the outlet of a sink, a collar depending from said outlet and having an annular external groove, a sleeve surrounding the grooved portion of said collar and having a plurality of holes therein opposite said groove, a ball in each of said holes and of a diameter greater than the thickness of the wall of said sleeve, a ring surrounding said sleeve and positioning said balls so as to project in said groove, a shell secured to said sleeve, and means reacting on said ring to clamp said collar against the wall of the sink defining the outlet therein.

2. In a garbage grinder adapted to be secured to the outlet of a sink, a flanged collar depending from said outlet and having annular external recess means, a sleeve surrounding said collar and having a plurality of holes therein opposite said recess means, a member in each of said holes, a

ring surrounding said sleeve and positioning said members so as to project into said recess means, means axially moving said ring relative to said collar for securing said sink between said ring and the flange of said collar, and a shell secured to said sleeve and defining a chamber for material to be reduced.

3. In a garbage grinder adapted to be secured to the outlet of a sink, a flanged collar depending from said outlet and having annular external recess means, a sleeve surrounding said collar and having a plurality of holes therein opposite said recess means, a member in each of said holes and projecting into said recess means, means axially moving said ring relative to said collar for securing said sink between said ring and the flange of said collar, and a shell depending from said sleeve and defining a reducing chamber.

4. In a garbage grinder adapted to be secured to the outlet of a sink, said sink being provided with a bottom wall having a drain opening, a supporting and sealing structure comprising a flanged collar adapted to extend through said drain opening with the flange of said collar engaging the upper surface of said bottom wall about said drain opening, said flanged collar having an annular external groove formed therein beneath said flange, a sleeve surrounding the groove portion of said collar and having a plurality of holes therein opposite said groove, said sleeve also having an outwardly projecting flange formed at the lower end thereof, a ball in each of said holes of a diameter greater than the wall thickness of said sleeve, a ring surrounding said sleeve and positioning said balls in said openings to project into said groove, a pair of flexible annular sealing gaskets, one of said gaskets being positioned about said collar between said ring and the lower wall of said sink and oppositely with respect to said flange on said collar, the other of said gaskets being positioned between said ring and said flange formed on said sleeve, a shell having an upper flange end associated with said last mentioned gasket and projecting inside said sleeve flange, threaded means adapted for axially moving said ring toward said sleeve flange for compressing said last mentioned gasket for securing and sealing the flange end of said shell, said threaded means being also adapted to compress said first mentioned gasket against said bottom wall for sealing said collar flange against said bottom wall and for supporting said structure.

5. In a garbage grinder adapted to be secured to the outlet of a sink, said sink being provided with a bottom wall having a drain opening, a supporting and sealing structure comprising a flanged collar adapted to extend through said drain opening with the flange of said collar engaging the upper surface of said bottom wall about said drain opening, said flanged collar having an annular external groove formed therein beneath said flange, a sleeve surrounding the groove portion of said collar and having a plurality of holes therein opposite said groove, said sleeve also having an outwardly projecting flange formed at the lower end thereof, a ball in each of said holes of a diameter greater than the wall thickness of said sleeve, a ring surrounding said sleeve and positioning said balls in said openings to project into said groove, a pair of flexible annular sealing gaskets, one of said gaskets being positioned about said collar between said ring and the lower wall of said sink and oppositely with respect to said flange on said collar, the other of said gaskets being posi-

tioned between said ring and said flange formed on said sleeve, a shell having an upper flange end associated with said last mentioned gasket and projecting inside said sleeve flange, means adapted for axially moving said ring toward one of said flanges for compressing one of said gaskets for securing and sealing said structure at said one flange, said means being also adapted to compress the other of said gaskets for securing and sealing the other of said flanges for supporting and sealing said garbage grinder upon said sink.

6. In a garbage grinder adapted to be secured to the outlet of a sink, said sink being provided with a bottom wall having a drain opening, a supporting structure comprising a flanged collar adapted to extend through said drain opening with the flange of said collar engaging the upper surface of said bottom wall about said drain opening, said flanged collar having an annular external groove formed therein beneath said flange, a sleeve surrounding the groove portion of said collar and having a plurality of holes therein opposite said groove, a ball in each of said holes of a diameter greater than the wall thickness of said sleeve, a ring surrounding said sleeve and positioning said balls in said openings to project into said groove, a flexible annular sealing gasket positioned about said collar between said ring and the lower wall of said sink and oppositely with respect to said flange on said collar, means adapted for axially moving said ring for compressing said gasket against said bottom wall for sealing said collar flange against said bottom wall and for supporting said structure.

7. In a garbage grinder adapted to be secured to the outlet of a sink, said sink being provided with a bottom wall having a drain opening, a supporting structure comprising a collar adapted to extend through said drain opening, said flanged collar having an annular external groove formed therein, a sleeve surrounding the groove portion of said collar and having a plurality of holes therein opposite said groove, said sleeve also having an outwardly projecting flange formed at the lower end thereof, a ball in each of said holes of a diameter greater than the wall thickness of said sleeve, a ring surrounding said sleeve and positioning said balls in said openings to project into said groove, a flexible annular sealing gasket positioned between said ring and said flange formed on said sleeve, a shell having an upper flange end associated with said gasket and projecting inside said sleeve flange, means adapted for axially moving said ring toward said sleeve flange for compressing said last mentioned gasket for securing and sealing the flange end of said shell for supporting said structure.

8. In a garbage grinder adapted to be secured to the outlet of a sink, said sink being provided with a bottom wall having a drain opening, a supporting structure comprising a flanged collar adapted to extend through said drain opening with the flange of said collar engaging the upper surface of said bottom wall about said drain opening, a sleeve surrounding said collar having an outwardly projecting flange formed at the lower end thereof, a ring surrounding said sleeve, attaching means associated with said ring for securing said collar and said sleeve together, a pair of flexible annular sealing gaskets, one of said gaskets being positioned about said collar between said ring and the lower wall of said sink and oppositely with respect to said flange on

said collar, the other of said gaskets being positioned between said ring and said flange formed on said sleeve, a shell having an upper flange end associated with said last mentioned gasket and projecting inside said sleeve flange, threaded means adapted for axially moving said ring toward said sleeve flange for compressing said last mentioned gasket for securing and sealing the flange end of said shell, said threaded means being also adapted to compress said first mentioned gasket against said bottom wall for sealing said collar flange against said bottom wall and for supporting said structure.

9. In a garbage grinder adapted to be secured to the outlet of a sink, said sink being provided with a bottom wall having a drain opening, a supporting structure comprising a flanged collar adapted to extend through said drain opening with the flange of said collar engaging the upper surface of said bottom wall about said drain opening, a sleeve surrounding said collar and having an outwardly projecting flange formed at the lower end thereof, a ring surrounding said sleeve, attaching means associated with said ring for securing said collar and said sleeve together, a pair of flexible annular sealing gaskets, one of said gaskets being positioned about said collar

5
10
15

between said ring and the lower wall of said sink and oppositely with respect to said flange on said collar, the other of said gaskets being positioned between said ring and said flange formed on said sleeve, a shell having an upper flange end associated with said last mentioned gasket and projecting inside said sleeve flange, means adapted for axially moving said ring toward one of said flanges for compressing one of said gaskets for securing and sealing said structure at said one flange, said means being also adapted to compress the other of said gaskets for securing and sealing the other of flanges for supporting and sealing said garbage grinder upon said sink.
